UNITED STATES PATENT OFFICE.

FRED E. ERICKSON, OF KREM, NORTH DAKOTA.

WHIP-SOCKET LOCK.

970,696.

Specification of Letters Patent. Patented Sept. 20, 1910.

Application filed February 25, 1910. Serial No. 545,809.

To all whom it may concern:

Be it known that I, FRED E. ERICKSON, a citizen of the United States, residing at Krem, in the county of Mercer, State of North Dakota, have invented certain new and useful Improvements in Whip-Socket Locks; and I do hereby declare the following to be a full, clear, and exact description of the invention, such as will enable others skilled in the art to which it appertains to make and use the same.

This invention relates to combined whip sockets and locks, and has for one of its objects to provide a device of this character so constructed that the whip may be inserted by forcing it downwardly which movement automatically locks the whip in the socket, but can be removed therefrom only by the application of a key.

With this and other objects in view, the invention consists in certain novel features of construction as hereinafter shown and described and then specifically pointed out in the claims; and, in the drawings illustrative of the preferred embodiment of the invention, Figure 1 is a side elevation of the whip socket constructed in accordance with the invention, Fig. 2 is a rear elevation of the same, Fig. 3 is a longitudinal section on the line 3—3 of Fig. 2, Fig. 4 is a transverse section on the line 4—4 of Fig. 1, Fig. 5 is a transverse section on the line 5—5 of Fig. 3, Fig. 6 is a detached perspective view of the key whereby the whip is released.

The improved device may be embodied in various forms of whip sockets, and to whip sockets constructed of various materials, and for the purpose of illustration is shown applied to a conventional form of whip socket represented as a whole at 10. The body of the socket is provided with bearing ribs 11 to provide means for holding the supporting straps whereby the socket is connected to a dash board, but as the means for coupling the socket to the dash board does not constitute a part of the present invention the holding means are not shown.

The interior of the socket near its lower end is converged as shown at 12 to form a guide for the lower end of the whip when the latter is inserted into the socket. Formed within the socket 10 just below the converging portion 12 is a seat 13, and supported within this seat is a semi-circular member 14 having open slots 15—16 in its terminals. Slidably disposed upon the seat is another

semi-circular member 17 with its terminals underlying the terminals of the member 14 and provided with upwardly directed pins 18—19 which extend through the slots 15—16. By this means the member 17 is movable toward and away from the member 14 and guided in its movement by the pins 18—19 operating in the guide slots 15—16. The member 17 extends normally for a distance within the opening defined by the contracted portion 12 and with the upper side of the member inclined as shown, so that as the butt end of the whip is inserted it will bear against the inclined face of the member 17 and move the latter outwardly to permit the whip to pass downwardly below the members 15—17, as hereinafter explained.

Formed upon the stock 10 at one side and opposite the seat 13 is a tubular extension 20, and formed upon the member 17 opposite the tubular extension is a stud 21 having an offset 22 preferably at its free end. Disposed within the extension 20 is a spring 23 bearing at its outer end against the outer end of the extension and at its inner end against the member 17, and thus maintaining the same yieldably in its inner position with the pins 18—19 bearing against the inner ends of the slots 15—16. Projecting from the tubular extension 20 is a key-guide or sleeve 24. The key employed in the tubular device is represented at 25, and is tubular so that it will fit over the stud 21 and is provided with an L-shaped slot 26 to engage over the pin 22, the operation to be hereinafter explained.

With a device thus constructed and secured in a convenient position upon the dash board the whip may be readily inserted from above and forced downwardly to cause its butt end to be guided through the opening between the members 14—17 and engage against the inclined face of the member 17 and force the latter outwardly against the resistance of the spring 23 until the enlargement of the rib upon the bottom of the whip stock passes beneath the members 14—17, when the reaction of the spring 23 will cause the member 17 to bear against the stock above its lower flange and thus effectually lock the whip stock within the socket.

When the whip is to be released the driver inserts the key 25 through the sleeve 24 and rotates the latter until the L-shaped slot 26

passes over the pin 22. The driver then rotates the key 24 still farther to cause the inner end of the slot 26 to pass over the stud 21 and thus couples the key to the stud. 5 Then by drawing the key outwardly the member 17 is withdrawn from engagement with the whip and releases the latter which may then be withdrawn from the socket.

The improved device is simple in construction, can be inexpensively manufactured and operates effectually for the purposes described.

What is claimed is:—

1. A whip socket having a transverse seat, 15 a stationary bearing member supported upon said seat and provided with guide slots, a movable bearing member slidably supported upon said seat and provided with guide pins extending through said slots, yieldable means 20 for supporting said movable bearing member, and a key operating to move said movable bearing member away from the stationary bearing member.

2. A whip socket having a transverse seat 25 and with a hollow projection opposite the seat, a stationary bearing member supported upon said seat and provided with guide slots, a movable bearing member slidably supported upon said seat and provided with 30 guide pins extending through said slots, a spring within said projection and bearing upon the movable bearing member, and a key operating through said projection to move said movable bearing member away 35 from the stationary bearing member.

3. A whip socket having a transverse seat and with a hollow projection opposite the seat, a stationary bearing member supported upon said seat, a movable bearing member 40 slidably supported upon said seat, a spring within the projection and bearing upon the

movable bearing member, a stud projecting from said movable bearing member and extending into said spring, said stud having a lateral offset, and a tubular key insertible 45 through said tubular projection and engaging over said stud and provided with an L-shaped slot for engaging with the offset of said stud and coupling the key to the stud.

4. A whip socket having a transverse seat and with a hollow projection opposite the seat, a stationary bearing member supported upon said seat and provided with guide slots, a movable bearing member slidably supported upon said seat and provided with 55 guide pins extending through said slots, a spring within said projection and bearing upon the movable bearing member, a stud extending from the movable bearing member and projecting into said spring, said stud having a lateral offset, and a tubular key operating through said projection and engaging over said stud and provided with an L-shaped slot to engage the offset of the stud. 60

5. A whip socket having a hollow projection at one side, a bearing member movable within said socket, a spring actuated within said projection and bearing upon the movable member, a stud projecting from said movable bearing member and extending into 70 said socket, said stud having a lateral offset, a tubular key insertible through said tubular projection and engaging over said stud and provided with an L-shaped slot for engaging with the offset of said stud and coupling the 75 key to the stud.

In testimony whereof, I affix my signature, in presence of two witnesses.

FRED E. ERICKSON.
